UNITED STATES PATENT OFFICE.

WILLIAM J. REGAN, OF WILKINSBURG, PENNSYLVANIA, ASSIGNOR TO THE McCONWAY & TORLEY COMPANY, OF PITTSBURGH, PENNSYLVANIA, A CORPORATION OF PENNSYLVANIA.

RAILWAY DRAFT APPLIANCE.

Application filed December 10, 1926. Serial No. 153,870.

My invention relates to draft appliances for railway cars and is particularly concerned with the production of a device which is well suited for application to light passenger cars. The principal object of the invention is to provide a simple, compact and efficient mechanism wherein the coupler is enabled to perform extended lateral swinging movements permitting the car to pass around curves with ease and safety.

The primary feature of the invention, generally stated, consists in constructing the draft appliance with a draft yoke to the forward end of which a coupler is pivotally connected, and in providing means for yieldingly maintaining the coupler and yoke in longitudinal alinement, said means comprising spring seats rigidly secured to the yoke on opposite sides thereof, followers in advance of the spring seats and movable with respect thereto, springs respectively positioned between the followers and the corresponding spring seats, and means carried by the coupler and adapted to cooperate with the followers to effect a compression of one or the other of the springs accordingly as the coupler swings to one side or the other from its normal position.

A further feature of the invention consists in providing opposite sides of the yoke in advance of the laterally extending spring seats thereof with a plurality of vertically spaced laterally projecting flange portions adapted to receive and form guides for the followers by which the coupler centering springs are compressed.

Other features of the invention residing in particular combinations of parts and advantageous details of construction will hereinafter appear and be pointed out in the claims.

In the drawings illustrating a preferred embodiment of the invention,—

Figure 1 is a plan view of a draft appliance embodying the invention, showing its relation to the draft sills of a car.

Figure 2 is a view, partly in side elevation and partly in vertical section, of the construction shown in Fig. 1.

Figure 3 is a view, partly in plan and partly in section, on the line 3—3, Fig. 2, a portion of the coupler being broken away.

Figure 4 is a sectional view on the line 4—4, Fig. 2.

Figure 5 is a sectional view on the line 5—5, Fig. 2.

Figure 6 is a sectional view on the line 6—6, Fig. 2.

In the drawings, 1 indicates the sills of the car with which the draft appliance is associated. Between these sills and riveted thereto is a draft casting 2 which provides front stops 3 and rear stops 4 for respectively cooperating with the front follower 5 and the rear follower 6 of the cushioning device for resisting draft and buffing forces. The draft spring 7 is interposed between the followers 5 and 6 and may advantageously be protected from injury, such as might result if it were allowed to compress solid, by providing each of the followers with cylindrical stops 8 which embrace the spring and maintain it in central position, the adjacent ends of the stops being adapted to abut so as to arrest the movement of the followers toward each other before the spring is fully compressed.

Instead of being made in two parts the draft casting 2 is preferably fashioned as an integral member which is open below so as to permit the draft yoke 9 to be assembled therewith from beneath. The yoke may be conveniently supported in assembled position by means of a carrier plate 10 bolted or otherwise secured to the draft sills 1.

At its forward end the draft yoke 9 is bifurcated to form an upper arm 11 and a lower arm 12 between which the rear end of the coupler 13 is received, the coupler being pivotally connected to the yoke by a pivot pin 14 which is preferably removable downwardly, and the rear end face of said coupler being cylindrically curved, as at 15, concentric with the pivot pin so as to cooperate with the correspondingly curved buffing bearing 16 with which the yoke 9 is provided. The lower arm 12 at the forward end of the yoke projects forwardly beyond the end of the upper arm 11, and each of said arms is in effect widened at its forward end by oppositely disposed laterally extending flanges 17 and 18, respectively, adapted to overlap the coupler when the latter

is in effect compressed. The flanges 17 and 18 are provided with a plurality of vertically spaced laterally projecting flange portions adapted to receive and form guides for the followers by which the coupler centering springs are compressed.

swings with respect to the yoke as the car passes around a curve. By this means the coupler is efficiently supported against drooping and horizontal alinement of the coupler and yoke is preserved in service.

In advance of the opening 19 for receiving the followers 5 and 6 and the draft spring 7, the draft yoke 9 is provided on opposite sides with laterally projecting spring seats 20 which preferably are integrally united to the yoke. These spring seats may advantageously be braced and reinforced by vertically spaced forwardly extending flanges 21 cast integral with the yoke and adjacent spring seats. The neighboring flanges 21 are spaced apart a sufficient distance to receive the coupler centering springs 22 which bear against the respective spring seats 20, said flanges thereby serving to house portions of the springs. The forward faces of the spring seats 20 are preferably provided with cylindrical studs 23 which serve to center the springs 22 and maintain them in proper bearing relation to the spring seats.

Cooperating with the forward end of each of the coupler centering springs 22 is a follower 24 adapted to move with respect to the yoke and to the coupler. The inner edges of these followers are guided by the neighboring sides of the draft yoke 9, while their outer edges are preferably flanged rearwardly, as indicated at 25, to afford extended bearing area for contact with the respectively adjacent inner faces of the draft sills 1. Each of the followers 24 is also preferably formed with a rearwardly extending cylindrical stud or boss 26 for centering the cooperating spring 22. At their forward ends the springs 22 are housed above and below by vertically spaced flanges 27 integrally united to the draft yoke 9 and projecting laterally therefrom. These flanges, which form guides for the followers 24, are shouldered on their opposed faces, as at 28, to provide stops for limiting the forward movements of the followers.

It will be perceived that when the device is in service the followers 24 are housed and guided at the top and bottom by the ribs or flanges 27 and on the inside by the sides of the yoke and on the outside by the draft sills or center sills of the car.

The coupler 13 is provided in advance of its pivotal axis with means for actuating the followers 24 to effect a compression of one or the other of the springs 22 when the coupler executes a pivotal movement with respect to the yoke 9. For this purpose the coupler is preferably formed on opposite sides with vertically spaced perforated lugs 29 between which are rollers 30 for cooperating with the corresponding followers 24. These rollers are journaled on pins 31 whose ends are upset or riveted so as to secure them to the lugs 29.

The reinforcing flanges 32 and 33 at the forward end of the draft casting 2 are spaced vertically so as to permit the spring seats 20 to move rearwardly between them in buffing, the upper flanges 32 preferably extending forwardly sufficiently far to overlap the respectively adjacent spring seats 20 when the parts are in normal relation and the lower flanges 33 being somewhat shorter so as to afford clearance permitting the assembled yoke and draft gear to be raised into assembled relation with the draft casting 2. The central rivets 34 at the forward end of the draft casting are countersunk to avoid interference with the spring seats 20, and the lower rivets 35 likewise have their inner ends countersunk in order to avoid interference with the spring seats 20 when the yoke is being raised from below to assembled position.

In assembling the mechanism the draft spring and cooperating followers and the centering springs 22 and their cooperating followers 24 are associated with the draft yoke 9 in assembled relation, and these parts are then raised from below and positioned in the draft casting 2. The rear carrier plate 10 and the forward carrier plate 36 are then secured in place and the coupler 13 is pivotally connected to the draft yoke.

On draft and buffing movements the draft spring 7 is compressed between the followers 5 and 6 in the well known manner. When the coupler swings with respect to the draft yoke 9 one or the other of the rollers 30 presses against the neighboring follower 24, thereby forcing the latter rearwardly and effecting a compression of the adjacent spring 22. When the force which has caused the coupler to be displaced laterally from its normal position ceases to act, the spring 22 expands and returns the cooperating follower 24 and roller 30 to normal position, thereby restoring the coupler to central position.

I claim:—

1. A railway draft appliance involving a draft yoke, a coupler pivotally connected to the forward end of the yoke, and means for yieldingly maintaining the coupler and yoke in longitudinal alinement, said means comprising spring seats carried by the yoke and disposed upon opposite sides of the latter, followers on opposite sides of the yoke in advance of the spring seats and movable with respect thereto, springs respectively positioned between the followers and corresponding spring seats, and means responsive to pivotal movements of the coupler with respect to the yoke for energizing said springs.

2. A railway draft appliance involving a draft yoke, a cushioning device associated with the yoke for resisting draft and buffing forces, a coupler pivotally connected to the yoke in advance of the cushioning device,

and yielding means for normally maintaining the coupler and yoke in longitudinal alinement, said means comprising spring seats rigidly secured to the yoke and disposed upon opposite sides of the latter, followers on opposite sides of the yoke in advance of the spring seats and movable with respect to the latter, said yoke being provided with means for limiting forward movement of the followers with respect to the spring seats, springs respectively positioned between the followers and corresponding spring seats, and means movable with the coupler for energizing said springs.

3. A railway draft appliance involving a draft yoke having an opening therein adapted to receive a cushioning device for resisting draft and buffering forces, a coupler pivotally connected to the yoke in advance of the opening, and means for normally maintaining the coupler and yoke in longitudinal alinement, said means comprising spring seats rigid with the yoke and disposed on opposite sides thereof, followers, means for limiting the movement of the followers away from the spring seats with which they respectively cooperate, and means revolvably mounted on opposite sides of the coupler for cooperating with respective followers to energize said springs.

4. A railway draft appliance involving a draft yoke, a coupler pivotally connected to the forward end of the yoke, said yoke being provided rearwardly of the point of pivotal connection of the coupler thereto with oppositely extending spring seats, and being provided on opposite sides in advance of said spring seats with vertically spaced portions, followers on opposite sides of the yoke positioned between said vertically spaced portions, springs respectively interposed between the followers and corresponding spring seats, and means carried by the coupler for cooperating with the followers to energize the springs.

5. A railway draft appliance involving a draft yoke, a coupler pivotally connected to the forward end of the yoke, said yoke being provided to the rear of the pivotal axis of the coupler with laterally projecting spring seats and being formed on each side in advance of said seats with a plurality of vertically spaced flanges, followers on opposite sides of the yoke positioned between adjacent flanges, said flanges being shouldered to provide stops for limiting forward movement of the followers, springs respectively positioned between the followers and the corresponding spring seats, and means cooperating with said followers for compressing the springs.

6. A railway draft appliance involving, in combination with draft sills, a draft yoke,

a coupler pivotally connected to the forward end of the yoke, and means for yieldingly maintaining the coupler and yoke in longitudinal alinement, said means comprising spring seats carried by the yoke and disposed on opposite sides of the latter, followers on opposite sides of the yoke in advance of the spring seats and movable with respect thereto, springs respectively interposed between the followers and corresponding spring seats, and means secured to the coupler for cooperating with the followers to compress the springs, said yoke being formed with portions for cooperating with the followers to guide the latter and the followers being disposed between the draft sills.

7. A railway draft appliance involving, in combination, a draft casting provided with front and rear follower stops, said casting being open at the bottom to permit a draft yoke to be assembled therewith from beneath, a draft yoke, a coupler pivotally connected to the forward end of the yoke, spring seats rigidly connected to the yoke and disposed on opposite sides of the latter, springs bearing against the corresponding spring seats, followers in advance of the spring seats and respectively cooperating with the springs, and means carried by the coupler for cooperating with the followers to energize the springs, said draft casting being provided at its forward end with a plurality of flanges which extend over the respectively adjacent spring seats.

8. A railway draft appliance involving a draft yoke, a coupler pivotally connected to the forward end of the yoke, and means for yieldingly maintaining the coupler and yoke in longitudinal alinement, said yoke being formed with an opening adapted to receive means for cushioning draft and buffering forces and having in advance of said opening a curved bearing face adapted to cooperate with the inner end of the coupler, and being formed at its forward end with vertically spaced arms between which the coupler is received, the lower arm extending forwardly beyond the upper arm, and each of said arms having laterally extending portions which overlap the coupler when the latter swings upon its pivot.

9. A draft yoke adapted to be pivotally connected to a car coupler, said yoke being provided with an opening for receiving means for cushioning draft and buffering forces and being provided in advance of said opening with oppositely extending spring seats and having on opposite sides at its forward end vertically spaced portions forming follower receiving recesses in longitudinal alinement with the respective spring seats.

In testimony whereof I affix my signature.
